LIGHTING FIXTURE

Arthur P. Ebrite, Chicago, Ill., assignor of one-half to E. C. Koegel, Chicago, Ill.

Application July 10, 1933, Serial No. 679,645
Renewed June 6, 1935

8 Claims. (Cl. 240—78)

My invention relates to illumination, and includes among its objects and advantages an extension of the effectiveness of indirect illumination to render that type of illumination more generally acceptable for the type of service best characterized as residential.

From the standpoint of illumination only, indirect illumination, as by flooding a light colored ceiling, wall, floor, or table with light, is much superior to direct illumination, but the equipment heretofore used for such lighting has been of a mechanical construction affording so little opportunity for esthetic and artistic effects that indirect lighting has made relatively little progress for residential use.

In the accompanying drawings:

Figure 1 is a side view of an overhead lighting fixture according to the invention, the right half of the figure being in elevation, and the left half in radial section;

Figure 2 is a bottom plan view on a reduced scale, of the unit of Figure 1;

Figure 3 is an enlarged section on line 3—3 of Figure 1;

Figure 4 is an enlarged section on line 4—4 of Figure 1;

Figure 5 is a side view of a unit suitable for a side lamp for a dressing table; and

Figure 6 is a section on line 6—6 of Figure 5.

In the embodiment of the invention selected for illustration in Figures 1 to 4, the bulk of the light from the source 10 impinges on the inner reflecting surface 12 of the sheet metal reflector 14, and is thus thrown upward to flood the ceiling with light. The reflector 14 includes a flat central bottom portion 16. Four radial slots are formed in the reflector beginning at 18 near the center of the flat bottom portion 16, and extending out and up the curved portion to terminate near the outer edge at 20. The portion of each slot extending up the curved portion is tapered.

Associated with each slot is a glass overlay 22 extending laterally as at 24 a short distance on each side of the slot. The glass in the overlay is translucent and may transmit a minor or a major fraction of the incident light. When the fraction transmitted is high, the outer surface of each overlay is of an irregular shape such as the double concave contour indicated at 26. By this irregular outer surface, the small fraction of the light emanating from the source 10 that enters the overlay is diffused on leaving so that no appreciable illumination is delivered to the room in this way, and the eyes of an observer looking directly at the overlay are not subjected to glare,

but perceive the overlay as an ornamental pattern on the unit, which pattern is illuminated but not a source of appreciable illumination or glare.

Each overlay includes an insert portion 28 in the form of a central rib shaped to fit the slot. The extended side portions 24 are of substantially constant width so that most of the overlay and the insert are tapered in general parallelism with the tapered walls of the slot, the taper being 10 clearly indicated at 30 in Figure 2.

Below the bottom 16 and below the horizontally and inwardly projecting inner end 32 of the overlays, is positioned a retainer 34, also of glass. The central portion of the retainer 34 lies against the 15 bottom 16, as indicated at 36 in Figure 1, and outside this central portion there is a peripheral groove 38 surrounded by an annular upstanding rib 40. The inner end of each overlay is fashioned to fit the rib 40 and groove 38, terminating in a 20 lug 42 resting in the groove.

In assembled position the outer end of each overlay is supported by an extension of the insert 28 clearly shown at 44 in Figure 1, which rests above the inner surface of the reflector. 25

The retainer 34 and all the inserts are fastened together into a unitary whole by a stud 46 having a bottom head 48, and a retaining nut 50 overlying the bottom 16.

The source 10 is mounted in the usual socket 52, 30 and the upper portion of the source and the socket 52 are enclosed in the usual husk 54. The husk 54 supports the reflector unit assembly by three equally spaced tension links 56.

The entire lighting unit is supported from the 35 usual plate 58 and central pipe 60. The sleeve 62 presents at 64 the smallest diameter of the inverted pedestal, and is threaded at 66 to receive a slip ring 68, which retains the canopy 70 in assembled position. The canopy 70 may have 40 additional support in the form of machine screws 72 at its outer edge. The lower end 74 of the sleeve 62 is of smaller diameter than the inside diameter of the screw threads on the slip ring 68, so that the slip ring can be unscrewed downwardly and pass downward over the portion 74 to rest on the upper end portion 76 of the husk, which end portion has the outer surface shape of part of a torus of approximately the same configuration and outer diameter as the slip ring 68 50 itself. In this way additional clearance is permitted for moving the canopy 70 downward to permit a workman to solder together the wire ends inside the canopy 70, and at the same time the general symmetry of the outer contour of 55

the pedestal is effectively maintained. The husk itself is supported by clamping the inner edge of the torus 16 between the upper end of the socket 52 and the opposing shoulder on the sleeve 62.

5 The same construction illustrated in Figure 1 is entirely suitable for use the other side up as a table lamp, except that the tension link 56 will be replaced by rigid wires or rods. Such construction being notoriously old and common in the art, 10 it is deemed unnecessary to encumber the drawings with this detail.

The embodiment of the invention selected for illustration in Figures 5 and 6 employs the same retainer 34 and stud 46 as the embodiment of 15 Figure 1. The reflector 80 is a cylinder with part of one side cut away at 82. The remainder of the reflector carries two overlays 84, which may be identical in cross section with the overlay 22, and which have similar insert portions 86.

20 The lower and inner ends 88 of the overlays are turned inwardly at right angles to conform to the shape of the reflector used, and carry lugs 90 identical with lugs 42 to cooperate with the groove 38 and annular rib 40.

25 In the positions where symmetry would call for additional overlays, but for the lateral cutting away of the reflector itself, symmetry in the inside illumination of the retainer 34 is maintained by openings 92 in the bottom 94.

30 The entire unit is supported by the stud 96 clamped directly to the reflector by a clamping nut 98 and provided with a suitable swivel connection at 100 tightened into frictional engagement by the knurled annulus 102. This permits 35 the user to adjust the position of the entire unit;—in case of a side lamp for a dressing table, by rotation about a vertical axis passing through the swivel connection to change the distribution of light inwardly or outwardly as desired.

40 It will be observed that without appreciable reduction in the engineering efficiency of the indirect illumination obtained, the type of construction above outlined affords opportunity for a wide variety of artistic effects that permit indirect 45 lighting fixtures to harmonize fully with various geometrical and color systems of interior decoration. More particularly, it permits a definition of an ornamental light pattern made up of straight or curved lines or bands defined substantially by 50 their own luminosity only. To render such a tracery pattern a contribution to the beauty of the whole rather than a subordinate source of illumination, the degree of illumination is kept low enough so that the eye is encouraged to dwell 55 directly on the light pattern, and may do so without eye strain.

Without further elaboration, the foregoing will so fully explain my invention that others may, by applying knowledge current at the time of application, readily adapt the same for use under various conditions of service.

I claim:

1. Indirect illumination equipment comprising a light source; a reflector shaped to reflect the light from the said source in a flood in a predetermined direction; said reflector having apertures, and inserts in said apertures; said inserts being of translucent material and having irregular outer surfaces, whereby the light passing through said outer surfaces is diffused sufficiently to render its illuminating action negligible; said inserts including portions overlying the unilluminated face of the reflector and forming an illuminated but not illuminating ornamental pattern on the otherwise dark side of the reflector; each insert 75

tending to a point near the axis of the reflector; a translucent retaining member symmetrical about the reflector axis; said retaining member and the inner ends of said inserts having interengaging irregularities of contour whereby said inserts are supported by said retaining member and restrained against radial movement; the outer ends of said inserts having extensions lying inside the reflector to support said outer ends of said inserts; said extensions extending longitudinally 10 but not laterally, whereby said inserts and retaining member may be assembled with said reflector by moving the inserts into position from outside and then positioning the retaining member under their inner ends. 15

2. Indirect illumination equipment comprising a light source; a reflector shaped to reflect the light from the said source in a flood in a predetermined direction; said reflector having apertures, and inserts in said apertures; said inserts being of translucent material and having irregular outer surfaces, whereby the light passing through said outer surfaces is diffused sufficiently to render its illuminating action negligible; said inserts including portions overlying the unilluminated face of 25 the reflector and forming an illuminated but not illuminating ornamental pattern on the otherwise dark side of the reflector; each insert extending to a point near the axis of the reflector; a translucent retaining member symmetrical about 30 the reflector axis; said retaining member and the inner ends of said inserts having interengaging irregularities of contour whereby said inserts are supported by said retaining member and restrained against radial movement. 35

3. Indirect illumination equipment comprising a light source; a reflector shaped to reflect the light from the said source in a flood in a predetermined direction; said reflector having apertures, and inserts in said apertures; said inserts being of translucent material and having irregular outer surfaces, whereby the light passing through said outer surfaces is diffused sufficiently to render its illuminating action negligible; said inserts including portions overlying the unilluminated face of 45 the reflector and forming an illuminated but not illuminating ornamental pattern on the otherwise dark side of the reflector; each insert extending to a point near the axis of the reflector; a retaining member symmetrical about the reflector 50 axis and substantially at the place of nearest approach of all said inserts; said retaining member and the inner ends of said inserts having interengaging irregularities of contour whereby said inserts are supported by said retaining member and restrained against radial movement. 55

4. Indirect illumination equipment comprising a light source; a reflector shaped to reflect the light from said source from the inner surface of said reflector in a flood in a predetermined direction; said reflector having apertures defining an ornamental pattern occupying only a minor fraction of the area of said reflector; elements of light transmitting material registering with said apertures, said elements having irregular outer 65 surfaces such that the light passing through them is diffused sufficiently to render its illuminating action negligible, whereby said elements constitute an illuminated ornamental pattern of such low intrinsic brilliance as to be comfortable 70 for direct vision with the naked eye; the outwardly projecting portion of each element having lateral portions overlying the outer surface of the reflector, and having lateral surfaces shaped to shed a halo on the closely adjacent 75

reflector surface and thus blur the outline of the pattern; and quickly detachable unitary retaining means for fastening all said elements positively in assembled relationship.

- 5 5. A reflector for indirect illumination comprising a main body shaped to reflect the light from a suitably positioned source in a flood in a predetermined direction; said body having apertures occupying only a minor fraction of the area of said body and defining an ornamental tracery pattern; elements of translucent material removably covering said apertures and extending at least partly outside the same, said elements dissipating and diffusing the light passing through them sufficiently to render its illuminating action negligible, whereby said elements when illuminated constitute an ornamental light pattern of such low intensity as to be noticeable but not brilliant, and comfortable for direct contemplation with the naked eye, and retaining means for fastening said elements to the reflector but permitting removal and replacement thereof.
- 10 6. Indirect illumination equipment comprising a light source; a reflector shaped to reflect the light from said source from the inner surface of said reflector in a flood in a predetermined direction; said reflector having apertures receiving light from said source; said apertures occupying only a minor fraction of the area of said reflector; removable diffusing means of translucent material intercepting all the light entering said apertures, whereby direct illumination through said apertures is completely cut off; said diffusing means being arranged in a tracery pattern lying along the outer reflector surface and being rendered luminous by the intercepted light but with such low intensity of illumination as to be noticeable but not brilliant, and comfortable for direct contemplation with the naked eye, under the conditions of illumination produced by the main flood of reflected light, and retaining means for fastening said material to the reflector, but permitting removal and replacement thereof.
- 15 7. Indirect illumination equipment comprising a light source; a reflector shaped to reflect the light from said source from the inner surface of said reflector in a flood in a predetermined direction; said reflector having apertures receiving light from said source; said apertures occupying only a minor fraction of the area of said reflector; removable diffusing means of translucent material intercepting all the light entering said apertures, whereby direct illumination through said apertures is completely cut off; said diffusing means being arranged in a tracery pattern lying along the outer reflector surface and being rendered luminous by the intercepted light but with such low intensity of illumination as to be noticeable but not brilliant, and comfortable for direct contemplation with the naked eye, under the conditions of illumination produced by the main flood of reflected light; said diffusing means including portions protruding through said apertures, and retaining means for fastening said material to the reflector, but permitting removal and replacement thereof.
- 20 8. Indirect illumination equipment comprising a light source; a reflector shaped to reflect the light from said source from the inner surface of said reflector in a flood in a predetermined direction; said reflector having apertures receiving light from said source; said apertures occupying only a minor fraction of the area of said reflector; removable diffusing means of translucent material intercepting all the light entering said apertures, whereby direct illumination through said apertures is completely cut off; said diffusing means being arranged in a tracery pattern lying along the outer reflector surface and being rendered luminous by the intercepted light but with such low intensity of illumination as to be noticeable but not brilliant, and comfortable for direct contemplation with the naked eye, under the conditions of illumination produced by the main flood of reflected light; said diffusing means including portions protruding through the apertures of the reflector, and portions lying outside the outer surface of the reflector to shed a halo on the adjacent reflector surface, and retaining means for fastening said material to the reflector, but permitting removal and replacement thereof.
- 25 9. Indirect illumination equipment comprising a light source; a reflector shaped to reflect the light from said source from the inner surface of said reflector in a flood in a predetermined direction; said reflector having apertures receiving light from said source; said apertures occupying only a minor fraction of the area of said reflector; removable diffusing means of translucent material intercepting all the light entering said apertures, whereby direct illumination through said apertures is completely cut off; said diffusing means being arranged in a tracery pattern lying along the outer reflector surface and being rendered luminous by the intercepted light but with such low intensity of illumination as to be noticeable but not brilliant, and comfortable for direct contemplation with the naked eye, under the conditions of illumination produced by the main flood of reflected light; said diffusing means including portions protruding through the apertures of the reflector, and portions lying outside the outer surface of the reflector to shed a halo on the adjacent reflector surface, and retaining means for fastening said material to the reflector, but permitting removal and replacement thereof.
- 30 10. Indirect illumination equipment comprising a light source; a reflector shaped to reflect the light from said source from the inner surface of said reflector in a flood in a predetermined direction; said reflector having apertures receiving light from said source; said apertures occupying only a minor fraction of the area of said reflector; removable diffusing means of translucent material intercepting all the light entering said apertures, whereby direct illumination through said apertures is completely cut off; said diffusing means being arranged in a tracery pattern lying along the outer reflector surface and being rendered luminous by the intercepted light but with such low intensity of illumination as to be noticeable but not brilliant, and comfortable for direct contemplation with the naked eye, under the conditions of illumination produced by the main flood of reflected light; said diffusing means including portions protruding through the apertures of the reflector, and portions lying outside the outer surface of the reflector to shed a halo on the adjacent reflector surface, and retaining means for fastening said material to the reflector, but permitting removal and replacement thereof.
- 35 11. Indirect illumination equipment comprising a light source; a reflector shaped to reflect the light from said source from the inner surface of said reflector in a flood in a predetermined direction; said reflector having apertures receiving light from said source; said apertures occupying only a minor fraction of the area of said reflector; removable diffusing means of translucent material intercepting all the light entering said apertures, whereby direct illumination through said apertures is completely cut off; said diffusing means being arranged in a tracery pattern lying along the outer reflector surface and being rendered luminous by the intercepted light but with such low intensity of illumination as to be noticeable but not brilliant, and comfortable for direct contemplation with the naked eye, under the conditions of illumination produced by the main flood of reflected light; said diffusing means including portions protruding through the apertures of the reflector, and portions lying outside the outer surface of the reflector to shed a halo on the adjacent reflector surface, and retaining means for fastening said material to the reflector, but permitting removal and replacement thereof.
- 40 12. Indirect illumination equipment comprising a light source; a reflector shaped to reflect the light from said source from the inner surface of said reflector in a flood in a predetermined direction; said reflector having apertures receiving light from said source; said apertures occupying only a minor fraction of the area of said reflector; removable diffusing means of translucent material intercepting all the light entering said apertures, whereby direct illumination through said apertures is completely cut off; said diffusing means being arranged in a tracery pattern lying along the outer reflector surface and being rendered luminous by the intercepted light but with such low intensity of illumination as to be noticeable but not brilliant, and comfortable for direct contemplation with the naked eye, under the conditions of illumination produced by the main flood of reflected light; said diffusing means including portions protruding through the apertures of the reflector, and portions lying outside the outer surface of the reflector to shed a halo on the adjacent reflector surface, and retaining means for fastening said material to the reflector, but permitting removal and replacement thereof.
